UNITED STATES PATENT OFFICE.

ALBERT WIEGEL, OF CASSEL, GERMANY.

SLEEVE HOLDER.

Application filed July 7, 1927, Serial No. 204,000, and in Germany May 5, 1926.

- This invention relates to a sleeve-holder for shirt-sleeves. The object of this invention is to wear the shirt-sleeves shortened in a most simple manner, in order to save the 5 wrist-bands.
- Hitherto elastic bands are made use of for such purpose, but these elastic bands have the disadvantage, that they firmly embrace the arm and produce a burdensome effect.
- To overcome said disadvantage I have provided a sleeve-holder consisting of a flat clasp, which is bent from wire. The opposite shanks of the clasp are formed as a ring in the middle.
- The new sleeve-holder is illustrated on the accompanying drawing by way of example. It is to be understood that I do not limit myself merely to the details of construction as shown, but that the scope of my invention 20 extends to whatever construction may be defined or included within the terms or language of the appended claim.
- In the drawing:
- Figure 1 is a plan view of the sleeve-holder.
- Figure 2 is a perspective view of the sleeve-holder, when it is in practical use.
- The sleeve-holder consists of a flat clasp, which is bent from elastic wire, the clasping shanks *b*, *b* lying tightly opposite to one another. In the middle of the clasp each shank 30 is bent to a semicircle, both halves completing one another to a circular ring *a*, the opposite halves of which are connected by a ball at each end.
- In this way the clasp ends in the grip on 35 both sides of said ring.
- The described sleeve-holder will be employed in the following manner:
- The clasp, which forms the sleeve-holder, is laid lengthwise on the shirt-sleeve. Then 40 the shirt-stuff is drawn through the ring and thereafter in the lateral grips.
- In this manner the stuff having been drawn up will be held in the grips without any damage. The shirt-sleeves may be shortened by 45 means of the described sleeve-holder to any desired degree.
- Having now particularly described my said invention, I declare that what I claim is:—
- A sleeve holder consisting of a flat clasp, 50 which is bent from thin elastic wire, the opposite halves of which are bent to a semicircle in the middle and are connected by a ball at each end.
- In testimony whereof, I have signed my 55 name to this specification.

ALBERT WIEGEL.
